UNITED STATES PATENT OFFICE.

GILBERT ALFRED CASSAGNES, OF PARIS, FRANCE.

PRINTING TELEGRAPHIC APPARATUS.

SPECIFICATION forming part of Letters Patent No. 460,349, dated September 29, 1891.

Application filed November 28, 1890. Serial No. 373,278. (No model.)

To all whom it may concern:

Be it known that I, GILBERT ALFRED CASSAGNES, of Paris, France, have invented an Improvement in a new Printing Telegraphic Apparatus, of which the following is a specification.

My invention relates to a new improvement in printing-telegraph apparatus, and pertains mainly to the printing-receiver.

10 The object of my invention is to construct a printing-telegraph apparatus which shall contain a new principle of construction over the patents previously granted to me, No. 307,841, of November 11, 1884; No. 313,175, of 15 March 3, 1885, and No. 313,176, of March 3, 1885.

Reference is had to the accompanying drawings, in which—

Figure 1 is a plan view of the key-board. Fig. 2 shows the appearance of one style of ribbon. 20 Fig. 3 is a plan view of a key-board and punching device. Fig. 4 shows the appearance of one style of ribbon after being perforated by the punching device. Fig. 5 is a plan view of an automatic transmitter, a ribbon connecting Figs. 3 and 5. Fig. 6 is an enlarged side elevation, showing arrangement of a part of the mechanism contained in the receiving-instrument. Fig. 7 is a perspective view of a receiving-instrument. Fig. 8 is an enlarged side view 25 of the same. Fig. 9 is a top view of the same. Fig. 10 is a side elevation of the cam-spindle A'. Fig. 11 is a side view of the type-wheel spindle. Fig. 12 is a face view of the type-wheels. Fig. 13 is a side elevation of the spindle-actuating motor. Fig. 14 is a cross-section on line 1 2, Fig. 10. Fig. 15 is a cross-section on line 3 4, Fig. 10. Fig. 16 is a cross-section on line 5 6, Fig. 10. Figs. 17 and 18 illustrate the direction of a circuit between 30 two points. Fig. 19 is a top view of a modified key-board and punching device. Figs. 20 and 21 illustrate two codes, showing, respectively, the difference between the phonetic and orthographic systems.

45 To facilitate an understanding of this invention a brief description of the key-board by which the letters of the receiver are caused to move is given. The key-board is illustrated by Fig. 1 of the drawings, and consists of, say, 50 twenty keys, ten on a side, thus forming two sets. Each of these sets is divided, as indicated by the dotted lines in said figure, so that

the first six keys from the left hand of the key-board will form one series and the remaining four keys of the same set will form the 55 second series. The first four keys of the second set will form the third series, and the remaining six keys of the same set the fourth series. The first series causes the first consonant of a syllable to print, the second series causes the 60 second consonant of a syllable to be produced, the third series causes the vowel of the syllable to be printed, and the fourth series produces the last consonant of a syllable, as I have already clearly explained and set forth in the 65 patent previously granted to me, No. 313,176, of March 3, 1885. In the manner well understood in steno-telegraphy these keys are capable of various combinations, which allow in this case a general total of seventy-four 70 combinations.

The key-board can be manipulated according to two distinct methods: (a) It can be manipulated according to a short-hand method, so as to reproduce speech or any text whatever 75 by means of phonetic sound, as illustrated by code No. 1, Fig. 20. (b) It may be manipulated by orthography, as is the case with telegraph-instruments now in use, to produce every letter of the word, as by code No. 2, Fig. 80 21. Of course this is only illustrative, as other combinations could be readily devised.

The receiving-instrument, hereinafter fully explained, causes a tape to be printed by type through the manipulation of the key-board 85 whether the key-board is operated according to the combination shown in code No. 1, Fig. 20, or the combination shown in code No. 2, Fig. 21. These tapes, when printed, carry short syllabic lines transversely, as shown on 90 Fig. 2, and may, according to the method of manipulation, represent simple phonetic sounds without orthography or the full orthography. It is obvious that the system of electric transmission between the key-board 95 and the receiving-instrument may vary. If the distance is short, each key of the board may be put in direct connection with the receiving-instrument, thus necessitating the use of twenty conductors to and one return-wire 100 from the receiver. Between two stations that are farther apart the keys of the key-board may be connected with contact-segments of a transmitting-distributer, the trailer of which

is kept in synchronism with the trailer of the receiving-distributer either by the processes patented to me on August 30, 1887, No. 368,931, and on December 27, 1887, No. 375,339, or by 5 any other well-known method. The contact-segments of the receiving-distributer should be electrically connected with the printing parts of the receiver. By this method a single line-wire may be used to transmit the signals.

The manipulation of the key-board of twenty keys in time with the uniform motion of a trailer on a distributor is practically impossible, and a direct connection between the 15 key-board and the distributor has the drawback of causing a great many contacts to be lost by the operator, thereby producing an inefficiency of the instruments. I therefore utilize a special punching-machine x , Fig. 3, 20 operated by a key-board of twenty keys, according to either code, and by which I am enabled to obtain from one hundred and eighty to two hundred words per minute with the phonetic system and from one hundred to 25 one hundred and twenty words per minute with the orthographic system, or even more, according to the skill of the operator. This speed, vastly superior to that of type-writing machines worked by the most skillful operators, is rendered possible by the manipulation and arrangement of my key-board. The hand of the operator once in place remains almost stationary and is so situated that the same finger can always operate the 30 same two keys. The combinations of two or three keys in each series are so chosen that they can be formed most rapidly—that is to say, everything is arranged in the key-board and in the choice of the combinations to arrive at the greatest possible rapidity of operation. Instead of printing a single letter at a 35 time, as with a type-writer, I am enabled to depress from one to twelve keys at a time and thereby perforate from one to ten separate letters or characters at the same time on one line of my ribbon. Each key in a key-board of this construction is connected with a cutter, so that when any key is depressed the corresponding cutter will perforate a 40 traveling tape. These perforations allow the 45 production of signals according to the processes of multiplex telegraphy, said signals being finally printed, as in Fig. 2, upon a tape at the receiving-station.

50 The punching-machine x , Fig. 3, and the automatic transmitter y , Fig. 5, are only represented diagrammatically on the drawings without any constructive details, as I make no claim with reference to these instruments. 55 The tape of the punching-machine can be punched according to three different arrangements: first, by placing the key-board on the punching-machine itself, in which case the keys operate directly and mechanically on 60 the punches, Fig. 3; second, by separating the key-board from the punching-machine and electrically connecting them by means of

a cable working the different electro-magnets $o o' o^2$, which act mechanically on the perforating-punches, Fig. 19; third, by acting 70 on these electro-magnets $o o' o^2$ with currents no longer produced by the depressions of the keys of a key-board, but arising from the motions of line-relays placed at a receiving-station.

The receiving-instrument consists of twenty electro-magnets $E E' E^2$, &c. (To make the description clearer, only three of these electro-magnets are shown in Fig. 6 of the drawings, which figure is merely introduced to facilitate the description and should not be understood to be a correct illustration of a working model.) The armatures $a a' a^2$, &c., of these electro-magnets are attached to rods $t t' t^2$, &c., which, when no current is actuating the electro-magnets, are pressed outward by the springs $h h' h^2$, &c., placed under the armatures. These rods $t t' t^2$ extend into corresponding slots $e e' e^2$, &c., of slide-bars $G G' G^2$, &c. These slide-bars are constantly drawn 85 to one side—say to the left—by a spring R , Fig. 6. The top slide-bar is longer than the others and has a shoulder g , which bears against the next lower and inner slide-bar, which is itself supplied with a shoulder which bears against 90 the next slide-bar, and so on, Fig. 8, for the purpose hereinafter specified. In front of this set of slide-bars is placed a spindle A . Upon this spindle four type-wheels $r r' r^2 r^3$ are hung, 95 Fig. 11. On the circumference of the first 100 type-wheel r are engraved the letters or groups of letters arising from the combination of the first six keys, which form the first series on the key-board. On the circumference of the second wheel r' are engraved the 105 letters or groups of letters arising from the combinations of the next four keys, forming the second series on the key-board. On the circumference of the next wheel r^2 are engraved the letters or groups of letters arising 110 from the combinations of the third series, and on the circumference of the remaining type-wheel r^3 are engraved the letters or sets 115 of letters which arise from the combinations of the keys in the fourth series. These type-wheels $r r' r^2 r^3$ are frictionally hung on the 120 spindle A . Each of these type-wheels is provided with a toothed snail $S S' S^2 S^3$, Figs. 6, 9, and 11. Each snail is provided with a 125 number of teeth equal to the number of letters on its corresponding type-wheel, and each snail is set at such an angle with regard to its type-wheel that when any tooth of the 130 said snail is caught by the horizontal slide-bar G , Fig. 6, the letter or group of letters corresponding to that tooth is stopped for that moment directly under the printing pad or roller T . Therefore if a current is passed through any one of the electro-magnets of the apparatus its armature is attracted, and the 135 rod t on this armature sets free the corresponding slide-bar by being retracted from the slot e .

The operation of the slide-bars which form

a combinator is based on the principle that if any one of them is set free then all the other slide-bars of the same set placed immediately above the one which has been set free 5 become free to move under the action of the spring R, and the linear distance through which they travel is equal to the distance fixed by the adjustment of the screw at the rear of that particular slide-bar which has 10 been set free. If two or three slide-bars are set free, the upper slide-bar will travel through a total distance made up of the sum of the two or three displacements of the two or three slide-bars set free. Moreover, the 15 slide-bars are so arranged that the action of a special cam on the fork R⁴, through the lever R³, pushes all the slide-bars back in their initial position. This is how this result is obtained, Fig. 6: If the rod t, for instance, is 20 depressed, the upper slide-bar G is set free and is drawn to the left by the spring R through a distance adjusted beforehand by means of the screw V. It catches the snail S and is pushed back in its initial position after the printing of the corresponding letter. 25 If the rod t' is depressed alone, the two slide-bars G and G' will move through a distance adjusted by means of the screw V', and after the printing of the corresponding letter, 30 when the upper slide-bar G is pushed back, it will carry back with it the slide-bar G' through the action of its shoulder g until that slide-bar G' is again locked in its initial position by the rod t' re-entering its 35 slot e'. If the rod t² is depressed alone, the three slide-bars G, G', and G² will move forward through the pulling action of the spring R, and the displacement will be that resulting from the adjustment of the screw V². The 40 upper slide-bar G pulls G' through its rod t, which has not left the slot e, and G' pulls G² through t', which has not left e'. After the printing of the corresponding letter, when G is pushed back, it will carry back with itself 45 the slide-bar G' through its shoulder g. G' will communicate this motion to G² through its shoulder g, and the set will be locked again in its initial position when the rod t² (the only one depressed) has re-entered its slot e², and 50 so on for the operation of the rods depressed one at a time. If two rods are depressed at a time—say t' and t², Fig. 6—then the operation will be the following: t' having left its slot, while t has not been depressed, the two slide-bars G and G' are set in motion by the spring R and travel through the distance adjusted by the screw V', which abuts against the lower slide-bar G². This last, being also set free 55 through the depression of the rod t², will be 60 drawn forward with the other two until V² abuts against the fixed frame of the instrument. The total distance traveled by the upper slide-bar G is therefore made up of the sum of the displacements of G' and G² as adjusted by the screws V' and V². If the three rods t, t', and t² are depressed at the same time, Fig. 6, G will travel through the dis-

tance determined by the adjustment of screw V, which abuts against G', and will carry G' forward until V' abuts against G². This 70 slide-bar G² will also follow the motion until its screw V² abuts against the fixed frame of the instrument in the case of Fig. 6 or against the next slide-bar G³, if there are more than three slide-bars, Fig. 8. The total displacement of the upper slide-bar G is in both cases 75 made up of the sum of the individual distances traveled by G, G', and G², respectively, as adjusted by the screws V, V', and V². They are all set back in their initial position 80 through the action of the cam acting on R³ and R⁴. The slide-bar G pushes back G', and G' pushes G² through their shoulders g g, Fig. 8, and the rods t t' t² will re-enter their respective slots e, e', and e², thereby locking 85 the system in its initial position.

In the case of a group of six slide-bars G to G⁵, Fig. 8, locked by the six rods t to t⁵ and provided with adjusting-screws V to V⁵ and shoulders g, the operation is the following: If 90 in such a system two rods—say t' and t²—are depressed at the same time, the upper slide-bar G, drawn by the spring R, will move toward the type-wheel, and its rod t, which has not been set free and therefore locks it with 95 G', will cause it to carry G' in its motion until the screw V' abuts against G². The rod t² being also depressed will allow G³ to follow the motion, urged as it is by the pressure communicated by the screw V', abutting 100 against G², and the rod t³, locking it with G³, until its own adjusting-screw V³ abuts against G⁴. The total displacement on the upper slide-bar G is therefore that made up of the sum of the distances traveled by G' and G³ 105 as adjusted by the screws V' and V³. The system will resume its initial position by the shoulders g of G, G', and G² acting each one in its turn until the rods t' and t² re-enter their respective slots e' and e³ and will be 110 ready for a new combination. For a combination of three rods—say t', t², and t³—depressed at the same time the two slide-bars G and G' will move together as they are interlocked by the rod t, which has not been 115 depressed. The screw V' will abut against G² after having traveled its adjusted stroke, and will carry forward the two next slide-bars G² and G³, which are interlocked by the undepressed rod t², until V³ abuts against G⁴. 120 A similar action is repeated on G⁴ and G⁵, which are also interlocked by the undepressed rod t³, until finally V⁵ abuts against the fixed frame. The total stroke of the upper slide-bar G is therefore that made up of the 125 preadjusted displacements of G', G³, and G⁵, and that upper slide-bar G will catch the tooth of the snail which corresponds to the combination. When the fork R⁴ is pushed back by the cam and the lever R³, the shoulders g of the slide-bars will act, each in its turn beginning with the upper slide-bar until the system is locked again by the rods t', t², 130 and t³ having re-entered their respective slots

e' , e^2 , and e^3 . Such is the principle on which the operations of my combinator are based and the different combinations of slide-bars rendered effective and the system forced back 5 in its initial position after the printing of the letters corresponding to the various combinations.

A second spindle A' , Fig. 10, is provided with cams $C C'$, set to effect the printing action of the pad T . Other cams $N N'$, Fig. 14, on this same spindle serve to push back the slide-bars $G G' G^2$, &c., to a position where they are again caught by the vertical rods t , $t' t^2$, &c., which are pushed into the slots $e e'$, e^2 , &c., by the springs $h h' h^2$, &c., (as explained,) and maintained in their position of rest until they are again released by said vertical rods, and so on. A spring R^3 draws the lever R^3 , by which the cams $N N'$ act on the 10 actuating-fork R^4 of the upper slide-bar G , back against the shaft A' . When the slide-bars $G G'$, &c., are pushed back, the teeth of the snails are freed, and the snails and type-wheels are again set in motion by the spindle A and 15 complete the revolution which they had begun when they were first set free and which had been interrupted by the action of the slide-bars on the snails. The rotation of the type-wheels is stopped at the zero-point (or 20 the space where there are no letters) by the catch M , Figs. 6, 11, and 12, which at every revolution of the shaft A' is released, as hereinafter explained, thereby allowing the type-wheels to make intermittent revolutions. If 25 it so happens that one of the type-wheels should not be called upon to print any letter, its corresponding set of slide-bars is of course at rest. This wheel will therefore be carried on by friction on the spindle A and 30 will go through a complete uninterrupted revolution, stopping again by the action of the catch M , while its neighbors will be stopped on the letters or groups of letters which they are required to print. The type-wheels are provided with equal divisions, on 35 which a single letter or a group of letters is engraved, according to the requirements of the method, and it therefore follows that a letter or a group of letters can be caused to 40 stop by the action of only one electro-magnet and the upper slide-bar; but in practice a letter or a group of letters may be stopped by the combined action of electro-magnets taken two at a time or three at a time, as 45 hereinbefore explained. When the printing of a syllable has been completed, the slide bar or bars are pressed back into the normal 50 position by the action of the cams $N N'$ through the medium of arms R^3 and R^4 and 55 the shoulders g on each slide-bar, that cause 60 the next lower bar to be pushed back at the same moment. The paper is advanced through the space between two consecutive lines by means of the special cam j , Fig. 10, operating 65 a pawl which engages the toothed wheel H , Fig. 9, so as to be ready for the printing of another syllable, and so on. The use of a

single snail for each series would necessitate a snail of (in this case) twenty-six teeth in the first and fourth series and eleven teeth in 70 the second and third. Hence for some of the combinations—those of the first and fourth series, for instance—this would have led to a displacement of the slide-bars much too considerable for a rapid instrument. I have therefore 75 divided each of the extreme snails S and S^3 into three sectors set one by the side of the other, Fig. 11, in such a way that the teeth of one of them will be in angular continuation of the teeth of the one before it, 80 as clearly shown by Fig. 12. On account of this arrangement of the snail in three sectors placed side by side on the same type-wheel I have introduced a corresponding modification in the constructive arrangement 85 of the upper slide-bars of the first and last series without in any way altering the principle of their operation, Fig. 9. It will be seen from the top view of the instrument, Fig. 9, that the first and fourth series are each 90 provided with three upper slide-bars, each of them intended to operate on one of the toothed sectors of the corresponding type-wheel. The sets of slide-bars in the first and fourth series consist, therefore, of four slide-bars arranged according to the principle 95 shown diagrammatically by Fig. 6, together with two lateral slide-bars placed one on each side of the upper slide-bar of the four just mentioned. According to the method of manipulation these two lateral slide-bars never form part of the same combination, and consequently are never called upon to operate at the same time. As is clearly shown in Figs. 8 and 9, they are each provided with a coil-spring, 100 which causes them to move forward toward their corresponding snail when their rods are released. Their adjusting-screws, when one or the other of them is operated, abut against the rear of the middle upper slide-bar. Consequently for combinations made up of one of these lateral upper slide-bars and of one or 105 two of the other slide-bars the lateral slide-bar will follow the motion of the middle upper slide-bar, which consists of the sum of the 110 strokes of the various slide-bars which have been released, but will always be at a distance of one tooth in front of the middle upper slide-bar through the previous adjustment of the screw placed at its rear extremity. The 115 toothed sectors being so arranged on the type-wheel that those which are to be operated by the lateral slide-bars precede in the order of rotation that which is operated by the middle upper slide-bar for all combinations in which 120 one of the lateral slide-bars comes into play, its corresponding toothed sector will be stopped at the required tooth before the wheel can turn round far enough to be operated by the middle slide-bar. It is seen, 125 therefore, that the lateral slide-bars need only travel through the distance corresponding to one tooth of the divided snail, and this considerably decreases the stroke which they 130

would otherwise have to make for a combination if the snail consisted of one continuous toothed spiral. This method of construction facilitates more rapid and smooth work on the part of the type-wheels and avoids the possibility of misadjustment on account of shocks. For the second and third series, as each snail only consists of eleven teeth, a similar arrangement is unnecessary, and the slide-bars and snails are constructed according to the principle shown diagrammatically by Fig. 6 and hereinbefore explained. The spindle A, upon which the type-wheels are mounted, may be driven by any suitable motor. Its speed does not require any mathematical precision. It need only be sufficient to carry the type-wheel from the zero position to the printing position with convenient rapidity, and, as soon as the slide-bars have set free the teeth of the snail, to continue to carry the type-wheels onto the zero position, where the wheel is checked by the stop M, and so on. A starting arrangement, Figs. 9 and 13, consists in a grooved pulley Z, mounted on a spindle P, Fig. 9. This spindle P is driven by the type-wheel spindle A through two gear-wheels Q and Q', set to reduce the speed to about half that of A. The spindle A', on which the various cams are set, is placed in a line with the spindle P, and is provided with a lever L, of which the left-hand extremity L' is hinged, and is pressed down by the spring Y, Fig. 13. At the two extremities of the lever L and L' are attached the ends of a string n, which string makes one or two turns around the groove of the pulley Z. W is a special electro-magnet for starting into motion the cam-spindle A' at the required instant. To attain this object, the end L' is held elevated by the upper part of the armature of the electro-magnet W, Fig. 13. In this position the hinged end L' of L loosens the string n around the groove of the pulley Z. The spindle P is then rotated, but the spindle A remains stationary. If a current is sent through the electro-magnet W, its armature is attracted, and the extremity L' of the lever L, being no longer supported, escapes and drops, thereby tightening the

string n on the grooved pulley Z. The spindle A' is then clutched on the spindle P and turned with it. After it has made one complete turn L' will meet again the upper part of the armature of the electro-magnet W, which is no longer attracted, the current having ceased to flow. L' is again closed against the spring Y and loosens the string n around the groove of the pulley Z, thereby unclutching the spindle A', which will stop again in this position, while the spindle P continues to rotate. The cam j, which works the lever of the paper-feed, bears at intervals against the lever, which is provided at one of its ends with a pawl working the teeth of a ratchet-wheel H, Fig. 9, and of the two feeding-rollers B b. Having now described my invention, I claim—

1. The combination, in a receiving printing-instrument, of series of printing-wheels $r r'$ 70 r^2 , &c., on the same shaft or carrier, with the corresponding series of toothed snails S S' S², &c., and with a corresponding series of superposed slides G G' G², &c., supporting-stems t t' t^2 , &c., and electro-magnets E E' E², &c., 75 all arranged for conjoint action upon one or more of said printing-wheels at one time, as set forth.

2. The combination of the printing-wheel r and its toothed snail S on the shaft A with 80 the cam-shaft A', lever R², springs R R², stem R⁴, slides G G' G², rods t t' t^2 , and electro-magnets E E' E², all arranged substantially as and for the purpose herein shown and described. 85

3. The combination of the sliding rods G G' G² with the adjusting-screws V V' V², rods t t' t^2 , and electro-magnets E E' E² for conjoint and separate action, substantially as and for the purpose herein shown and described. 90

In testimony that I claim the foregoing as my invention I have hereto signed my name, in presence of two witnesses, this 27th day of October, 1890.

GILBERT ALFRED CASSAGNES.
